Patented Aug. 9, 1921.

UNITED STATES PATENT OFFICE.

FRANK N. GILBERT, OF BINGHAMTON, NEW YORK, ASSIGNOR OF ONE-HALF TO
FRANCIS R. GILBERT, OF PHILADELPHIA, PENNSYLVANIA.

POCKET PENCIL, PEN, AND PAD HOLDER.

1,386,700.

Specification of Letters Patent. Patented Aug. 9, 1921.

Application filed August 15, 1918. Serial No. 250,006.

To all whom it may concern:

Be it known that I, FRANK N. GILBERT, a citizen of the United States, residing at Binghamton, in the county of Broome and State of New York, have invented certain new and useful Improvements in Pocket Pencil, Pen, and Pad Holder, of which the following is a specification.

The present invention relates to a stationary article case or holder adapted to be carried in the pocket, and has for an object to facilitate the carrying of pencils, pens, pads, and other articles found convenient for writing and making memorandums.

This invention provides a case which admits the easy insertion of pencils and pens in the case; which holds the pens and pencils from accidental displacement and protects the points of the same; which conveniently holds pads and memorandum slips in position for immediate use when the case is opened; wherein the clothing is protected from contact with the articles; which when removed from the pocket opens like a book; and which provides means for the retention of loose cards or sheets with data or notes thereon.

The above, and other important objects and advantages of this invention will be in part described in, and in part understood from, the following detailed description of the present preferred embodiment, the same being illustrated in the accompanying drawing, wherein;

Figure 1 is a plan view of a stationary article holder constructed according to this invention, the holder being unfolded.

Fig. 2 is an edge view of the holder, folded, certain parts being omitted.

Fig. 3 is a similar view, showing the device adjusted for supporting short pens or pencils.

Fig. 4 is a perspective view of the holder in open position ready for use.

Fig. 5 is a detail perspective view of one form of pad which may be used with this improved holder.

Fig. 6 is a fragmentary end view of one of the flaps or sections of the holder, showing a modified means for carrying memorandum slips.

Fig. 7 is a transverse section through one end of one of the flaps, showing a further modified form of sheet holding means.

Referring to the drawing, wherein like parts are designated by similar characters of reference throughout the several views, A designates the body portion of the holder which is in the form of a flat strip of leather, paper, or other suitable material or combination thereof. This body portion A is folded into substantially equal lengths to form folds or sections 3, 3' and 3''. The folded portion of the body between the sections 3' and 3'' is folded inwardly on the line 4' to provide short folds or guides as will presently appear, and designated as 4, 4.

The infolded portion 4, 4 is perforated along the line 4' to provide socket openings 5 and 5' for the reception of pencils and a fountain pen or the like. The portion 4, 4 is reinforced by the provision of a strip 6 secured preferably to the inner side thereof, and comprising any suitable material.

The section 3'' is adapted to carry a pad 75 of blank paper, and for this purpose may be provided with a slot 7 for the reception of the tongue α of the usual form of pad shown in Fig. 5. The section 3'' has a relatively stiff tongue 8 on its outer side which is adapted to engage between the leaves of the ordinary pad E which may be used in lieu of the pad of Fig. 5.

On the inner face of the section 3 is placed one or more tongues 9, 9' adapted to hold 85 sheets f which may have been removed from the pad E. The tongue 9 is preferably arranged at one side of the section 3 to facilitate the introduction and removal of the sheet f.

In Fig. 6 the loose card or sheet h is held to the section 3 by a clip 10, shown in the present instance as of the detachable type, and may be further secured by a pocket strip 11 which is carried by the section 3 near or at its outer end and into which the end of the card h is to be inserted. The pocket strip 11 may be secured to the section 3 by overturned flanges 12 on the section which are glued or otherwise fastened 100 to the strip 11, as shown, in Fig. 7.

The section 3'' has, near its free end, a transverse fold line b providing an end flap y adapted to be turned up into the position shown in Fig. 3 for supporting short pens and the like.

In use, the section 3'' is first folded over upon the middle section 3', and with the pen-

cil socket portion 4, 4 projecting inwardly. The pad is now mounted upon the exposed side of the first or inner section 3'', and the case may be closed by folding the outer section 3 over upon the inner section 3''.

The sides 4, 4 form inclined guides adapted to receive the points of pencils and the like and direct them into the socket openings 5, 5'. The pencils, designated at *d*, are 10 adapted to fit into the smaller openings 5 and the fountain pen or other relatively larger article *e* is adapted to fit into the larger opening 5'.

Initially, the pencil points may rest in 15 the bottom of the case between the sections 3 and 3' at the line of fold therebetween, but when the pencils become shorter by use the end flap *y* may be folded up between the section 3'' and the middle section 3' to form 20 a ledge or shelf for the pencil points. The flap *y* provides means for maintaining the ends of the pencils at all times in position for easy grasping.

What I claim is:

25 1. In a pocket pen and pad holder, a rectangular flat blank body portion composed of leather or other flexible material adapted to be folded in folds of even length to provide sides for the holder, one of the folds 30 being reentrant and lying between the sides of the holder, the said reentrant fold being provided with openings to receive a pen or

pencil, and a reinforcing strip secured to the body portion about said openings.

2. A pocket stationery case including a 35 flat strip folded over on a transverse line to provide sides for the case and having at its fold an inturned reentrant perforated portion forming guides for a pencil point and sockets for the reception of the pencil.

40 3. A pocket stationery case including a flat strip folded on a transverse line to provide sides for the case and having at its fold an inturned perforated portion forming guides for a pencil point and sockets for the 45 reception of a pencil, the free end of one of said sides being adapted to be folded over to form a seat in which the points of the pencils are adapted to be supported.

4. A pocket stationery case comprising a 50 flat strip folded on transverse lines to provide sides and a flap for the case, the fold between the sides being inturned and perforated to form guides for pencil points and sockets for the pencils, and means on the 55 outer face of one of the sides for supporting a writing pad.

In testimony whereof I have affixed my signature in the presence of two witnesses.

FRANK N. GILBERT.
